SHEET FEED

Ferdinand Nigra and Max E. Toby, San Francisco, Calif., assignors to Niagara Duplicator Co., San Francisco, Calif.

Application August 2, 1940, Serial No. 349,750

9 Claims. (CL 271—42)

The invention relates to a device for effecting the primary advancement of a sheet of paper or the like from a stack of the sheets to a mechanism which is to operate upon the sheet.

An object of the invention is to provide a sheet-feeding device of the character described which is particularly adapted for use with a rotary duplicator of the character of that described in U. S. Patent No. 2,089,979 of August 17, 1937.

Another object is to provide an improved sheet-feeding device which is structurally independent of a tray providing a stack of sheets to be printed, and may be actuated by a drive mechanism such as that disclosed in the aforesaid patent.

A further object is to provide a sheet-feeding device which applies a drag shoe in such a manner that the initial pressure of engagement of the shoe with the sheet to be moved exceeds the working pressure of the shoe during the movement of the sheet, said working pressure being constant.

An added object is to provide a particularly simple and positive control for the shoe during its return stroke during which it is free from the sheets on the supply stack.

The invention possesses other objects and features of advantage, some of which, with the foregoing, will be set forth or be apparent in the following description of a typical embodiment of the invention, and in the accompanying drawings, in which,

Figure 1 is a fragmentary side elevation of a duplicator having the primary sheet feed of my invention operatively associated therewith.

Figure 2 is an enlarged fragmentary section taken at the line 2—2 in Figure 1.

Figure 3 is an enlarged elevation of a dogging device of Figure 1.

Figure 4 is a perspective view of the feed mechanism and a tray from which sheets are to be fed thereto.

Figure 5 is a partially sectional and somewhat diagrammatic elevation of the mechanism, the parts being related as at the end of a working stroke of the drag shoe.

Figures 6 and 7 are elevations of the mechanism at the ends of the second and third cyclic movements of the shoe.

As shown, the present sheet feed has been adapted for successively supplying sheets 7 of paper or the like to a duplicating machine having a stencil or printing matrix carried on a rotary cylinder 8 for the printing engagement of the advance sheet between the printing element and an impression roller 9. While otherwise appli-

cable, the device is particularly shown as applied to the structure of the duplicating machine disclosed in said patent, No. 2,089,979, whereof the printing element comprises a stencil sheet. The printing cylinder 8 is supported on a shaft 13 for rotation on and between side frame members 10 and 11 which extend upwardly and in mutual opposition from a rectangular base frame 12 and receive the duplicator mechanism between them, and suitable means (not shown) are provided for rotating the cylinder for effecting printing cycles thereof.

Referring particularly to the somewhat diagrammatic showing of Figure 5, a sheet 7 of print-receiving material which has been moved from a feed table or tray 18 by the operation of the present device to position its front end portion between pairs of upper and lower rollers 16 and 17 may be thereafter engaged by and between 15 said rollers to advance it for the disposal of its front end portion between the printing element on the rotary cylinder 8 and the impression roller 9, and is finally gripped between the cylinder and the impression roller to continue the feeding 20 movement of the sheet while the latter is being printed.

The impression roller 9 is mounted for its free rotation on a shaft 19 which is carried by and between corresponding and forward ends of lever-like members 20 which are intermediately pivoted on a fixedly disposed rock-shaft 21, said shaft being journaled in and between the frame members 10 and 11 and being disposed toward the rear or feeding end of the machine with respect to the roller 9. The rear ends of the lever members 20 are connected by a bar 22, a tension spring 23 extends generally forwardly from the bar 22 to an anchorage in the frame 11 to constantly urge a resilient engagement of the impression roller 9 against the cylinder 8, and means are provided to rock the levers 20 to dispose the roller 18 out of engagement with the cylinder.

The rollers 16 are mounted on a shaft 28 which is loosely journaled in and between the upper 45 ends of lever-like members 29 which are disposed in generally upright position and are intermediately pivoted on the shaft 21 for rocking independently of the latter shaft. Preferably, and as shown, the upper lever portions are curved rearwardly to dispose the shaft 28 directly above the line of lower feed rollers 17 for the cooperation of complementary pairs of feed rollers to grip a sheet 7 between them. The lower arms of the levers 29 are connected to the side frame members 50 10 and 11 by means of tension springs 31 opera-

tive in the planes of movement of the levers whereby the levers are yieldingly urged to maintain their engagement with adjustable stops 32 which are provided on the frame members and while the rollers 16 are in a limiting lowered position with respect to the axis of the rollers 17.

A fixedly disposed shaft 33 carries the rollers 17, and said rollers are segmental whereby their cylindrical face portions extend through an arc which is somewhat less than a full circle. The rollers 17 have like perimeters and are similarly positioned on the shaft 33 whereby they may simultaneously coact in like manner with the rollers 16 above them. As the rollers 17 are rotated, their cylindrical faces are arranged to engage and grip a sheet 7 between them and the rollers 16 at a line at or adjacent the common plane of the shafts 28 and 33, it being noted that the rollers 17 coact with the rollers 16 only for the part of a rotative cycle thereof during which their cylindrical faces are in opposition to the latter rollers. Preferably, and as shown, the circles of the cylindrical faces of the rollers 17 are arranged to intersect the circles of the depressed rollers 16 whereby the latter rollers may be pressed upwardly against the resistance of the springs 31, and an equalized and resilient gripping of the sheet 14 between the sets of rollers 16 and 17 is thus assured while the rollers are coactive in the described manner.

A plate member 34 is fixedly mounted in and between the frame members 10 and 11 in generally horizontal disposition and in a plane slightly below the rollers 16 for the feeding movement of a sheet 7 thereover, and rectangular openings are provided in the plate opposite the segmental rollers 17 to permit the described periodic coaction of the rollers 16 and 17 therethrough. In the line of the openings for the rollers 17, other openings are provided, and the plate material at the advance edges of the latter openings is offset upwardly of the plane of the plate at the openings to provide a straight line of stops 35 against which the advance edge of a sheet 7 is arranged to abut when the sheet is initially advanced from the feed table 18. Forwardly of the line of stops 35, the plate 34 slopes upwardly in generally tangential relation to the cylindric face. The rear portion of the plate 34 extends downwardly to a support element of the frame.

Means are provided for lifting a front sheet edge out of engagement with the line of stops 35 at the proper time in a cycle of operations of the cylinder 8 whereby the sheet 7 may then be advanced by the rollers 16 and 17. In the present structure, flat fingers 36 are hingedly mounted on a fixed cross-member of the frame below the plate for swinging into and through the various plate openings opposite the stops 35. The fingers 36 overlie the shaft 33 and each is provided with a depending projection which is arranged to constantly and similarly ride on the top of the shaft, said shaft being cylindrical thereat except for a segmental notch provided therein. When the finger projections engage the bottoms of the underlying shaft notches, the fingers 36 are arranged to be disposed in the plate openings in coplanar relation therewith, whereby they may then provide a portion of the support surface for a sheet 7 as it is moved against the stops 35. When the finger projections ride on the cylindrical part of the engaged shaft surface, the fingers are raised to lift the front edge portion of the positioned

sheet clear of the stops 35 to thereafter permit a further advance of the sheet for its printing. Spring-pressed fingers 38 resiliently engage the tops of the lifting fingers 36 or with a sheet 7 which is disposed over the latter fingers. The fingers 38 insure a directing of the sheet 7 to an initial engagement with the stops 35 as the sheet is inserted between the then spaced rollers 16 and 17, no parts of the cam-like rollers 17 protruding above the plate 34 during the latter process.

It will now be noted that the positioning of a sheet 7 against the stops 35 is arranged to be effected by the operation of a drag shoe 39 against the top sheet 7 of a supply stack of sheets. The shoe 39 is actuated from the cylinder drive means in such synchronism with the operation of the shaft 33 as to move the top sheet 7 forwardly from the stack to effect a buckling engagement of the engaged sheet 7 against the stops 35 as the first operative step with respect to the printing of a sheet, and the present invention particularly concerns the control of the shoe 39 in the desired manner and sequence by the duplicator actuating mechanism.

The required operations of the shafts 21 and 33 and of the shoe 39 are primarily derived from the controlled reciprocative movement of a bar 41 which pivotally engages an arm 42 extending rigidly from the shaft 21 and is forked at its upper end to span a hub 40 extending from an end of the cylinder 8. The bar 41 is disposed in generally upright position in parallel relation to the frame side 10, and a plate cam 43 is fixedly mounted on the cylinder hub adjacent and inwardly of the forked portion of the bar 41. At its inner side, and in the plane of the cam 43, the bar 41 carries a roller 44 for periodic engagement by the cam to lower the bar and so oscillate the shaft 21 as is required for controlling the disposal of the impression roller 9. It will be noted that the spring 26 for the shaft 21 is operative to urge the upward disposal of the arm 42 and the bar 41.

An actuator element 45 is pivoted to the frame side 10 adjacent the plane of operation of the bar 41 and comprises a flat plate providing a segmental gear 46, an arm 47, and a radial slot 48. A roller 49 is mounted at the outer face of the bar 41 and constantly engages in the slot 48 whereby the element 45 is arranged for oscillation about its pivotal axis as the bar 41 is reciprocated, said axis being fixed. The segmental gear 46 is utilized to effect the periodic rotation of the shaft 33 which carries the segmental feed rollers 17 through the operation of a pinion 51 which it constantly engages and which is connected with the shaft 33 through a suitable one-way clutch 52 in such a manner that the shaft 33 is rotated only by and during a return movement of the element 45 to its normal position which is shown in Figure 1. It will be understood that it is this rotation of the shaft 33 which periodically effects the described operative rotation of the segmental rollers 17 at the appropriate time in each rotative cycle of the printing cylinder 8.

An arm 53 overlies the cylinder hub 40, is pivoted to the frame member 10 at its forward end, and carries a roller 55 which is arranged to constantly and gravitationally rest on the periphery of a plate cam 54 which is mounted on the hub beside the cam 43. A link 56 extends from the free end of the arm 53, and a link 57 ex-

tends from the arm 47 of the actuator member 45; the links 56 and 57 are utilized for cyclically controlling the positioning of the drag shoe 39 in a manner to be hereinafter described.

It will now be noted that the drag shoe 39 is carried at the rear end of an arm 58, and comprises a pair of axially aligned and spaced segmental elements providing friction faces of rubber or the like and non-rotatably mounted on the arm for engaging a sheet 7. The other end of the arm 58 is fixed on a bar 61 extending horizontally and across the forward end of the tray space. As shown, the bar 61 is intermediately slotted longitudinally thereof, and a thumb screw 62 extends from the forward arm end and through the slot of the bar 61 for clamping the arm to the bar in adjusted position therewith; this adjusted mounting of the shoe on the bar 61 provides for a centering of the shoe over the sheets on the feed table 18.

A rock shaft 63 is suitably journalled in and between bearings provided on the frame members 10 and 11 below the level of the bar 61, and is provided with arms 64 fixed thereto and extending upwardly to pivotal connections with the bar 61 which is parallel to the shaft 63. As particularly shown, the bar 61 is provided with down-turned terminal extensions or ears 65 and 66 which receive the upper ends of the arm 64 between them and are pivoted to said arm ends at pivot pins 67. An arm 68 extends rigidly from the shaft 63, and a spring 69 is constantly coactive between the arm 68 and an anchorage 11 on the frame member 11 to yieldingly urge a rearwardly swung positioning of the rock frame provided by the assembly of the shaft 63 and arms 64.

An arm 72 is pivotally mounted on the shaft 63 adjacent a fixed arm 64 of the shaft, and the free end of the arm 72 is provided with a pin or roller 73 extending parallel with said shaft and engaging in a slot 74 provided in the extension 66 below its pivot pin 67 and extending generally radially of said pin, it being noted that the extension 66 is L-shaped in elevation and provides a rearwardly extending arm portion 75 below its slot 74. The link 57 from the actuator arm 47 is pivotally connected to the arm 72 at an intermediate point thereof whereby longitudinal reciprocations of the link 57 are arranged to operate through the pin 73 and the extension 66 to oscillate the rock frame of the shaft 63 and arms 64 for effecting working and return strokes of the shoe 39, it being noted that the bearing of the shoe on the top sheet of the paper on the feed table 18 will limit the rocking of the bar 61 about its pivotal axis on the arms 64, provided the bar is free to rock on the arms. The latter condition is arranged to obtain when a forward, and working, stroke of the shoe is being effected by reason of a rocking of the actuator element 45 from its position of Figure 1 to its position of Figure 4.

It will be noted that the present swinging mounting of the drag shoe 39 on the arms 64 and its actuation by the link 57 through the engagement of the pin 73 in slot 74 of the bar extension 66 is such that a working movement of the shoe resting on the top sheet 7 provides a constant pressure engagement of the shoe which is slightly less than the static pressure which obtains at the start of the working stroke of the shoe. This pressure relation results from the fact that during a working stroke of the drag shoe 39, the shoe is pressed against the top sheet 75

of the stack of sheets by a total force including both that of the spring 69 and the additional pressure caused by the swinging of the shoe-carrying bar 61 about its axis of pivoting at the pins 67 by the link 57 acting through the pin 73 of the arm 72 in the slot 74 of the bar extension 66. Under static conditions at the start of a working stroke, the pull on the link 57 first creates a shoe pressure which increases until a forward dragging component thereof sets the paper in motion with the accompanying forward swinging of the arm 64 against resistance of the spring 69. As soon as the motion of the freed top sheet begins, the part of the starting pressure caused by the pull of the link 57 is immediately lessened. As the shoe is swinging forwardly on the arms 64, the pin 73 moves upwardly in the slot 74 whereby the effective lever arm for rocking is lessened, with the result that the portion of the shoe pressure produced by the swinging of the bar is automatically lessened. In practice, this progressive decrease in the shoe pressure created by the rising engagement of the pin 73 in the slot 74 is arranged to be greater than the natural increase in the resistance of the spring 69; thus, the sheet-engaging pressure of the shoe is in fact greatest at the beginning of a working stroke thereof both before and at the start of the shoe motion. Also, the shoe is operative in the same manner and for the same length of stroke over the stack regardless of the depth of the stack of sheets in the tray, this by reason of the disclosed rearwardly offset relation of slot 74 to a plane parallel to it and including the pivotal axis 35 of the bar 61.

When the engaged sheet 7 has been advanced against the stops 35 to slightly buckle the sheet between the stops and shoe in the manner indicated in Figure 4, the forward shoe motion ceases and the shoe is raised to permit a rearward flattening out of the advanced sheet while its front edge is lightly held between the fingers 36 and 38, this insuring a proper positioning of the paper for its subsequent forward feeding for its printing. The said lifting of the shoe to release the paper is arranged to be effected by rocking the bar 61 about its pivotal axis on the rock frame arms 64 while said arms are disposed forwardly at the end of the working stroke of the shoe.

As shown, the free end of the arm 75 carries a roller 76, and a cam arm 77 is provided in the plane of movement of the roller 76 for engagement beneath the roller to rock the arm 75 and bar 61 for swinging the shoe upwardly from the sheet. The cam arm 77 is shown as being pivoted to the frame member 10 at a point forwardly of the shaft 63, is intermediately connected by the link 56 to the arm 68, and has its upper edge providing a cam face 78 for such lifting engagement of the roller 76 of the arm 75 as to effect and maintain an inoperative positioning of the shoe 39 at the end of a working stroke and during a return stroke thereof. The portion of the cam face 78 which is engaged beneath the roller 76 when the cam arm 77 is fully raised is straight, and is then so disposed that the return path of the raised shoe is substantially parallel to the tray bottom. The plate cam 54 which controls the arm 77 through the arm 53 and link 56 has a profile comprising arcuate portions of different radius connected by tangents and of such relative lengths that the arm 77 is respectively raised and lowered at the ends of the working and return strokes of the shoe 39.

Means are provided for insuring a freeing of the top sheet 7 of a stack of sheets on the table 18 as the sheet is individually advanced by the action of the shoe 39 upon it. As particularly shown in Figures 1 to 3, complementary side wall members 81 are mounted on the table top 82 for receiving a stack of sheets 7 between them in the tray space thus defined. The members 81 are relatively adjustable to and from each other, have mutually inturned bottom flanges 83, and are provided with mutually opposite and upright slots 84. The slots 84 serve as guideways for weight members 85 secured for sliding vertically along the outer plate sides by means of headed extensions 86 slidably fitting the slots. The head portion 87 of each weight extension 86 is formed to provide an acute-angled edge 88 extending obliquely downwardly to the plane of the inner wall face whereby said edge may overlie a stack of sheets in the tray when the stack is closely fitted between the walls 81.

The tray bottom 82 is formed with an upward and forwardly inclined offset portion 89 adjacent its forward end, said end registering with the rear end of the horizontal portion of the plate 34 of the duplicator mechanism and the offset 89 providing a positioning stop for a stack of sheets in the tray. Particularly when a stack of sheets in the tray has been reduced to but a few sheets and is relatively flexible, the stack may tend to slide forwardly over the stop 89 under the influence of a working stroke of the drag shoe upon it; to prevent such a displacement of the reduced stack, the tray bottom 82 is preferably roughened, at least beneath the zone of action of the shoe, to insure a holding frictional engagement thereof with the bottom sheet of the stack; a thin surfacing coating 90 of carborundum or the like is preferred.

When a stack of sheets 7 is first placed on the table 18 with its front end in contact with the positioning stop provided by the offset 89, the weight members 85 are inoperatively disposed and the walls are adjusted laterally of the table top 82 to fittedly receive the stack between them. The weight members 85 are then lowered in the respective slots 84 to rest their heads 87 upon the stack sides whereby their edges 88 obliquely engage along the edges of the top sheets of the stack to wedgedly urge the engaged sheet edges inwardly of the stack side planes and so slightly lift at least the top sheet by buckling it to admit air beneath it adjacent the contact points; in this manner, cohesive and air-pressure binding of the top sheet with the underlying sheet is broken, and resistance to the forward movement of the sheet by the shoe 39 is minimized while the remainder of the sheets are held in place by the edges 88.

Assuming that the cylinder 8 is continuously rotating and that each cycle of operations of the shoe 39 begins with the shoe disposed in its limiting rear position while resiliently bearing against the top sheet of a stack of sheets in the tray, as shown in Figure 1, the first cyclic step comprises the forward movement of the shoe to dispose and slightly buckle the top sheet 7 against the line of stops 35 of the plate 34. This step is accomplished by the rocking of the actuator 45 from its position of Figure 1 to its limiting position of Figure 4, it being understood that neither the shaft 33 of the segmental feed roller 17 nor the arm 53 is affected during this movement of the actuator.

Having the parts as in Figure 4, the continued

rotation of the cylinder 8 operates to raise the arm 53 and so lift the cam arm 71 to rock the bar 41 to fully lift the shoe with respect to the sheet, it being recalled that the first lifting of the shoe releases the sheet to flatten out rearwardly. The return stroke of the actuator 45 not only raises the sheet from the stops 35 and propels it forwardly by action of the rolls 16 and 17, but also swings the arm 72 rearwardly to effect a return movement of the shoe 39 to its position of Figure 6 while the shoe is held in raised position by the action of the cam 54. After the drag shoe reaches its limiting rear position, the continued rotation of the cam 54 lowers the arm 71 to permit the shoe to resiliently bear upon the new top sheet in the stack for the repetition of the cycle; the actuator 45 is inactive during this step.

Means are provided for rendering the entire sheet feeding mechanism inoperative while leaving the cylinder rotatable as for the placement or removal of a stencil with respect to it, said means comprising a pawl or dog member 91 which is operative against the actuator member 45 when the bar 41 is in its lowest position to secure the member against a return swinging to its normal position and so eliminate working and return strokes of the shoe 39 and rotation of the shaft 33. As particularly shown in Figure 5, the dog 91 is intermediately pivoted to the frame member 10 so that it may extend generally tangentially of the circle of movement of the tip of the actuator arm 41 to dispose its tooth 92 slightly within said circle. A notch 94 is provided across the extremity of the arm 41 for receiving the dog tooth 92; when the dog is free to act, the outer end of the arm 41 is arranged to displace the dog to pass under it as the member 45 approaches the limit of the stroke caused by the lowering of the bar 41 and so operatively engage the pawl tooth in the notch 94 to permit a very slight return movement of the actuator which does not affect the shaft 33 or the shoe positioning.

When the described primary sheet feed is to be used, the dog 91 is held out of arm-engaging position by a suitable means. As particularly shown, a bell crank lever 95 is pivoted on the plate 10 above the pivotal point of the dog 91 and has one arm 96 thereof operative as a cam against and along the top of the dog and its other arm 97 providing a setting handle for the cam arm. The arrangement is such that the lever 95 may be disposed to engage the contact point 98 of its arm 96 with the dog at a point beyond its pivotal axis, the dog then being held to dispose its tooth out of the path of movement of the notch 94, as is shown in Figure 5. It will be understood that the line of pressure of the dog 91 against the cam arm 96 of the lever 95 is eccentric to the pivotal axis of the lever whereby the lever is releasably held in its operative position. When the arm 96 is swung to dispose the contact point 98 at the same side of the common plane of the pawl and lever axes, the dog is freed to function as a locking means for the actuator by engagement of its tooth in the notch 94 of the arm 41 when the latter starts a return stroke.

Recalling that the spring 69 constantly urges a rearward swinging of the rock frame which carries the shoe 39, and that the actuator element 45 would usually be free of the bar 41 which disposed it for the operatic engagement of the dog 91 with it, a release setting of the lever 95 must actually effect a freeing of the element only at the proper time in a rotation cycle of the printing cylinder 8. To this end, the bearing point 98

of the cam arm 96 comprises the outer extremity of a spring-pressed member 99 which extends in and from a radial socket in the arm 96 for a limited degree of protrusion therefrom, and the dog tooth 92 so engages the notch 94 that the urge to a return stroke of the element under the influence of the spring 26 retains the dog in the notch against the yielding urge of the member 99 to free the dog as it moves to its limiting release position in which it urges a rocking of the dog to dispose its point out of the path of travel of the actuator arm 49. Having the dog 91 operatively engaging the actuator 45, an inoperative disposal of the dog may be effected by the spring pressed member 99 only as the downward movement of the bar 41 is completed to rock the actuator to free the dog tooth from the notch and so permit the member 99 to act to swing the dog to an inoperative position in which it is held while the feeding mechanism is in use. In this manner, the sheet-feeding mechanism may operate only in synchronism with the cylinder.

From the foregoing description taken in connection with the accompanying drawings, the advantages of the construction and method of operation will be readily understood by those skilled in the art to which the invention appertains. While we have described the features and the principle of operation of a structure which we now consider to be a preferred embodiment of our invention, we desire to have it understood that the showing is primarily illustrative, and that such changes may be made, when desired, as fall within the scope of the following claims.

We claim:

1. In combination with a printing machine, a feed table fixedly related to the machine and adapted to support a stack of sheets for their successive feeding to the machine while the stack bottom remains at a constant level, a friction drag shoe for reciprocation over the stack, means to resiliently engage the shoe with the top sheet on the stack during a forward working stroke thereof, means to disengage the shoe from the stack of sheets during a return stroke thereof, and means automatically operative to reciprocate the shoe in synchronism with the printing operations of the machine.

2. A structure in accordance with claim 1 having the shoe and its operating means supported on the frame of the machine independently of the support of the feed table.

3. In a paper feed, a fixed table for supporting a supply stack of sheets, a rock frame for oscillation about an axis parallel to the table bottom and perpendicular to the path of advancement of sheets from the table, a support member mounted on the frame for rotation about an axis parallel to the frame axis and above the stack, a drag shoe for reciprocation over the stack, means mounting said shoe on said support member in fixed relation thereto and in spaced relation from the axis of rotation of the member, means to oscillate the frame for effecting working and return strokes of the shoe, and means operative to lower the shoe upon the top sheet of the stack during each working stroke thereof and to dispose the shoe out of contact with the stack during its return stroke.

4. A structure in accordance with claim 3 whereof the last means is operative directly upon and through the support member in synchronism with the rocking of the frame by the frame-oscillating means.

5. In a paper feed, a fixedly disposed table for supporting a supply stack of sheets in fixed position for their successive feeding from the top of the stack, a friction drag shoe for operative engagement with the top sheet of the stack, a rock frame carrying said shoe for effecting working and return strokes thereof, and means operative to effect like working strokes of the shoe for successive sheets of the stack at their different levels.

6. In a paper feed, a fixedly disposed table for supporting a supply stack of sheets in fixed position for their successive feeding from the top of the stack, a friction drag shoe for operative engagement with successive sheets of the stack to advance them against a fixed stop, a rock frame carrying said shoe for effecting working and return strokes thereof, and means operative to effect like working strokes of the shoe for successive sheets of the stack at their different levels.

7. In a sheet feed for a printing machine, a table providing a tray for a supply stack of sheets and fixedly related to the machine, a rock frame mounted on the machine for oscillation about an axis parallel to the table and perpendicular to the path of advancement of sheets from the table to the printing mechanism of the machine, an elongated support member mounted on the frame to overlie the stack and for its rotation about an axis parallel to the axis of oscillation of the frame, a drag shoe, means mounting said shoe on said support member in fixed relation thereto and in spaced relation from the axis of rotation of the member, means operative from the machine mechanism and through the support member to oscillate the frame for effecting working and return strokes of the shoe, and means operative from the machine mechanism and directly upon the support member to lower the shoe upon the top sheet of the stack during each working stroke thereof and to dispose the shoe out of contact with the stack during its return strokes.

8. In combination with a printing machine, a fixed feed table adapted to support a stack of sheets for their successive feeding to the machine, a friction drag shoe for reciprocation over the stack, means to resiliently engage the shoe with the top sheet on the stack with a progressively decreasing pressure during each forward stroke thereof, means to disengage the shoe from the stack of sheets during each return stroke thereof, and means wholly in advance of the shoe automatically operative to reciprocate the shoe in synchronism with the printing operations of the machine.

9. A structure in accordance with claim 7 wherein the last means comprises a movable track member.

FERDINAND NIGRA.
MAX E. TOBY.
